UNITED STATES PATENT OFFICE.

WILLIAM VINCENT FOLEY, OF NEW BRUNSWICK, NEW JERSEY.

PICTURE-PROJECTING APPARATUS.

1,273,843.

Specification of Letters Patent. Patented July 30, 1918.

Application filed September 18, 1917. Serial No. 191,926.

To all whom it may concern:

Be it known that I, WILLIAM VINCENT FOLEY, a citizen of the United States, residing at New Brunswick, in the county of 5 Middlesex and State of New Jersey, have invented certain new and useful Improvements in Picture-Projecting Apparatus and Reflectors Therefor and for other Purposes, of which the following is a specification.

10 This invention is an improvement in picture projecting machines and also in reflectors therefor and for all other purposes, including search lights, head-lights for motor cars, and reflectors for use with sources of 15 light in offices, dwellings, etc.

In the accompanying drawings forming a part hereof and illustrating the principle of this invention in the best mode now known to me,

20 Figure 1 is a central lengthwise vertical section of my new picture-projecting machine and of my new reflector. This view is taken at a line corresponding to line 2—2 of Fig. 2.

25 Fig. 2 is a top plan elevation of the machine shown in Fig. 1.

Fig. 3 is a front, and

Fig. 4 a rear elevation of my new reflector, removed; and

30 Fig. 5 is an edge view thereof.

The object of the invention is to produce a reflector particularly adapted for use in connection with incandescent electric lamp bulbs and of a construction and mode of operation that conserve to a greater extent than heretofore in illumination, the light rays proceeding from the source of light. Various kinds or types of sources of light may be used and I do not intend herein to 35

40 limit my invention, so far as the reflector itself is concerned, to use in connection with electric incandescent lamps, for my reflector may be used with any appropriate source of light with new beneficial results; and I note

45 that when it is used as a reflector in any way in which its concave reflecting surface is visible, such surface is of itself ornamental both when illuminated and when not illuminated.

Considered with reference to use of the 50 reflector in picture-projecting machines and especially with reference to motion picture machines, objects and advantages of my invention considered as a whole are: My new machine can be used to advantage because 55 its function is to produce two or more reflected images of the source of light and

in concentrating or focusing the light rays from said images on one or more given points; it can be used with an electric lamp bulb of appropriate candle power instead of 60 with arc-lights now in frequent use in motion picture projecting machines, and with various attending economical advantages; and it is constructed with a forced air ventilation whereby the life of the incandescent 65 lamp bulb and of the reflecting surfaces if they are of silvered glass are advantageously prolonged.

Referring to the drawings, the concave surface of the concavo-convex casing 1 is 70 lined at its bottom with a preferably parabolic mirror 2, and from the annular line or edge of the mirror 2 to the brim or edge of the casing, with two series of flat-faced reflecting surfaces which in the inward series are indicated by 3 and in the outward series by 4. All these mirror surfaces 3 and 4 of which there are a multiplicity in each series, are made of one concavo-convex mirror of any suitable material but ordinarily 80 of glass silvered on its back, in order to prevent refraction which would occur if they were made in separate edgewise-abutted pieces; the concavo-convex structure having a smaller rear opening at 5 to fit the brim 85 of the rearmost concave mirror 2 and a larger front opening adjacent the front brim of the disk-shaped casing.

The flat mirror surfaces 3 are polygonally disposed in the transverse direction, that is 90 in the circumferential cross-sectional direction of the casing, each being disposed at an angle to the other; and each is disposed slantingly upwardly and outwardly at an angle to a central axis through the casing. 95 The flat mirror surfaces 4 have a corresponding polygonal relation one to the other and are severally slanted upwardly and outward.

I employ a considerable number of these 100 mirror surfaces 3 and 4 in each series, the number of such surfaces being variable and the number of series of such flat mirror surfaces being also variable.

The number of the flat mirror surfaces 3 and 4 in each series depends largely on the size of the filament 6 or other source of light, and the number of series of the flat mirror surfaces 3 and 4 will depend largely on the depth of the reflector as a whole. 110

In relation to the size and dimensions of each flat mirror surface, the best rule for

determination thereof is, according to my experimentation up to date, to make each of a size, shape and dimension which will wholly reflect one and not more than one 5 complete image of the source of light which in this case, as shown, is the filament 6; but as filaments vary in shape, size, form and dimensions, the areas and shapes of the mirror surfaces 3 and 4 may be varied accordingly; and while I have used in practice and have also shown herein two series 10 of the flat mirror surfaces 3 and 4, it may well be that curvature of such surfaces would be equally or approximately as efficient as the flat mirror surfaces, and I do not intend to limit my invention to details by changes in which my invention, in relation to the form of the reflecting surfaces, 15 can be avoided. The fact is, according to my present information, that I am the first to produce a concave reflecting surface which is characterized by a multiplicity of polygonally disposed reflecting surfaces to inclose 20 a source of light and reflect a multiplicity of images of the source of light. The result of such arrangements is to concentrate or focus the rays of light from such multiplicity of images on the object or objects to be illuminated with an attendant brilliancy of 25 illumination strikingly in excess of that obtained from the use of any other reflector known to me.

The reflector is for picture projection mounted in a box 7 as at 8. The electric 30 light bulb 9 is mounted within the concavity of the reflector, an edge of the latter and of the casing being recessed at 10 to permit the location of the bulb and its contained filament in the concavity. The bulb-socket 40 11 is supported in an opening in the box-top. The electric lamp, for use in projecting pictures, is preferably of a size to fill and project from the concavity of the mirror with an air space left between the bulb and 45 the opposed wall of the reflector.

The box is provided at its lower portion with an air-intake port 12 from which the air-supply tube 13 extends, the tube being provided with a fan 14 for blowing air into 50 the box-chamber where it flows upwardly into and around the reflector and light bulb, cooling the surfaces thereof and carrying off the heat through the vent 15 in the top wall of the box. This cooling is of economic importance for reasons stated. The fan is 55 driven in any suitable way and its operation produces a positive current through the box chamber while the machine is in use. Forwardly of the reflector and source of light, 60 the box is equipped with suitable lenses 16, shown in a well-known form of condenser lens.

The parabolic or concave bottom-forming mirror 2 and the flaring arrangement of the 65 polygonally arranged reflecting surfaces 3

and 4 forwardly of the parabolic mirror 2, constitute the most effective form of my new mirror that I have yet devised in connection with the electric light bulb which must be inserted into the chamber of the mirror 70 structure in front of the bottom-forming mirror 2, and to obtain the best effect from a side of the mirror-forming structure so as to leave the mirror 2 intact; and in order that all the mirrors may coact to reflect the 75 light rays properly into and through the condenser lens structure. For the purposes of this invention the coöperating concave bottom reflector and the reflecting surfaces 3 and 4 must coöperate with the light for 80 reflection of the light rays to the condenser lens in such wise that the light rays must pass parallel one to the other through the condenser lenses at right-angles to the flat surfaces of the lenses, which flat surfaces 85 are directly opposed to the bottom concave lens. After passing in parallelism through the condenser lens, the light rays become focused at a point beyond the condenser lens. 90

I am aware of Gray's Patent No. 1,133,955 of March 30, 1915, in which an apparatus for photographic enlargement is set forth and in which the reflector and incandescent electric lamp are so arranged that the axis 95 of the lamp is in alinement with the point on which the reflected rays converge in the lens tube. In this Gray patent it is stated that maximum efficiency on the part of a reflector of his type, and when used in connection with the photographic enlarging apparatus, can be had only when the maximum number of reflected rays are directed into the lens barrel and they are shown converging in the lens tube or barrel, and obviously 100 converge at the center of whatever kind of lens is assumed to be in the tube. There is no suggestion in the Gray patent that the lens is a condensing lens, and Gray's drawing and description plainly indicate that 105 there is no intention to pass rays in parallelism through the lens so that they can converge at a focal point beyond the lens and exteriorly of the structure. I therefore disclaim all that is shown in the Gray 110 patent. 115

What I claim is:

1. In a picture-projecting machine, the combination of an incandescent electric light bulb, with a condenser lens and a mirror, 120 the bulb being intermediate the lens and mirror, and the mirror comprising a bottom-forming concave mirror and an outwardly flaring mirror having a plurality of sets of plane mirrors which in each set are angularly disposed one to another. 125

2. A structure as specified in claim 1, wherein said series of angularly disposed mirrors are integral.

3. In the structure of claim 1, the com- 130

bination of an interiorly and outwardly flar-
ing mirror casing having a lamp-receiving
opening in its side wall forwardly of its
bottom portion; and as a central lining of
its bottom portion, a concave bottom-form-
ing mirror; and as a lining for its interior
side wall forwardly of such bottom-forming
mirror, a plurality of series of mirrors, the
mirrors of each series being at an angle one

to the other; and in such side-wall mirror 10
lining, an opening for reception of an elec-
tric light bulb, such opening being coincident
with the opening in the side wall of the
casing.

In testimony whereof I have hereunto set 15
my hand this 15th day of September, 1917.

WILLIAM VINCENT FOLEY.
